UNITED STATES PATENT OFFICE.

GUSTAV A. HARTER, OF CHICAGO, ILLINOIS.

ELECTRIC FIXTURE.

1,249,389.

Specification of Letters Patent. Patented Dec. 11, 1917.

Application filed August 18, 1913. Serial No. 785,259.

To all whom it may concern:

Be it known that I, GUSTAV A. HARTER, a citizen of the United States, residing at Chicago, in the county of Cook and State 5 of Illinois, have invented certain new and useful Improvements in Electric Fixtures, of which the following is a specification.

This invention relates to a fixture particularly adapted for use in connection with 10 the electric lamps in which the lamp socket, and the lamp globes and shades may be separately adjusted and held relatively to each other.

The invention consists in the features of 15 novelty in the construction, combination and arrangement of the several parts generally shown in the accompanying drawings and described in the specification but more particularly pointed out in the appended claims.

20 In the drawings, Figure 1 is a side elevation of a fixture with the shade and globe in sections embodying my invention; Fig. 2 is a sectional view of the socket clamping device; Fig. 3 is a detail view partly in section of a part of the fixture; Fig. 4 is a cross-sectional view of a locking device; Fig. 5 is a sectional elevation of the locking device; Fig. 6 shows the fixture supporting 25 a ceiling plate with an adjustable eccentric support for the fixture; Fig. 7 is a detail of the eccentric adjustable support, and Fig. 8 shows the fixture in connection with the different form of shade or globe.

30

It is very desirable to have a support for 35 electric shades and globes, as well as for lamp sockets, which may be freely adjusted to accommodate various sizes and shapes of shades, globes and lamps, and also to provide means for facilitating the connection 40 of the lamp socket with the plug or conduit to which the fixture is secured. The present invention is for a fixture of this class.

A yoke member 10 comprises two parallel 45 extremities joined by a substantially flat perforated intermediate portion 11, the edges 12 of which are adapted to embrace an angular headed nut 13 which is internally threaded throughout its length and externally threaded for a portion of its 50 length, the externally threaded portion being adapted to be inserted through the perforation of the intermediate portion 11.

The parallel extremities are formed adjacent their ends with a portion 14 of re-

duced width forming a shouldered head 55 or extremity 15. Slidable up and down along the portion of reduced width are the extremities of a pair of socket clamping members 16 which are less in width than the length of the portion of reduced width so 60 that they may be moved up and down with respect to the yoke member 10 for adjustment. These socket clamping members 16 are connected and clamped against the extremities of the yoke member by means of 65 screws 17. A socket 18 is clamped by the screws in position between the clamping devices and the socket is separately movable with respect to the clamping members, and, of course, is movable with the members 70 when they are adjusted with respect to the yoke member. The object of this adjustment is not only to raise and lower the lamp in the socket but is also to provide a space between the yoke and the socket by means 75 of which conductors 19, connected to the socket, may be joined to other conductors projecting through the plug or from a conduit 20 by means of which the fixture is supported. A globe or shade-holding device 80 comprises two parallel arms 21 provided with threaded perforations which extend between the parallel extremities of the yoke member 10 and the fastening screws 17 on each side, and the extremities of the yoke 85 member are also provided with unthreaded perforations, and screws 22 are inserted through the yoke members and threaded into the arms 21, whereby the height of the shade-holding device may be adjusted independently, as desired. In order to lock the screws 22 in place a locking clip 23 is provided on each side of the yoke member which partially embraces the extremity of the yoke member and the arm 21, as shown more 90 clearly in Fig. 4, and is slidable thereon with an enlarged portion 24 to engage the head of the screw 22 to prevent it from being disengaged from its connection. The shade-holding device also preferably comprises adjustable members 25 by means of 95 which a globe or shade 26 may be held in position.

The fixture is supported by threading the member 13 upon the end of a plug or a conduit 20, and a shade 27 may be provided with an extending portion which covers the 100 adjustable part of the fixture and socket. 105

holding devices and also covers the adjustable members 25 of the globe holders. This shade 27 is provided with a perforation which adapts it to be inserted over the member 13 with a washer 28 between them, and it is secured in place thereon by means of an outer lock-nut 29 with a washer 30 between them. These washers are of resilient or flexible material so that the shade will not be injured in securing it in position.

If desired, the globe or shade-holding device may consist of a threaded member 31 (see Fig. 6) to which the arms 21 are connected, and a threaded member 32 having a projecting flanged portion to which shade-holding devices 33 are adjustable to hold a shade of any size in position, the flanged portion also acting as a support for a ceiling plate 34.

In order to provide an alining means for a number of fixtures a support device comprising spaced members 35 and 36 is secured to the yoke member, and it in turn is secured to the ceiling or other support by means of screws 37 inserted through parallel slots 38 in one of the members. This same member is also provided with an opening 39 extending in one direction from the center parallel with the slots 38 through which the conduit 20 extends. By adjusting this support relatively with respect to the conduit it may be alined in any direction an amount equal to the length of adjustment of the conduit in the slot 39.

Another embodiment of the invention is shown in Fig. 8, in which the shade-holding device comprises a frusto-conical support 40 secured to the arms 21 upon which the upper edge of a shade 41 is engaged. In this construction the yoke member is secured directly to conduit 20 and a hood 42 is adjustable upon the conduit and held in place by a screw 43, the hood covering the fixture and engaging the screws 23 to prevent their removal with the lower edge of the hood pressing against the globe or shade 41 to hold it firmly in position.

It is to be understood that this fixture is intended to accommodate globes and shades of various sizes and it is customary to have globes of various sizes with the same size supporting portion.

What I claim is:

1. A device of the class described comprising a U-shaped yoke member, a pair of socket clamping members each having extremities to engage the edges of the extremities of the U-shaped member, and fastening means to adjustably secure the socket clamping members together at both of their extremities and to permit the adjustment of the members upon the extremities of the U-shaped member.

2. A device of the class described comprising a single yoke member with parallel

extremities, the parallel extremities of which are reduced in width adjacent the ends thereof, socket clamping members each having extremities to engage the edges of the yoke member in the portion of the reduced width thereof, and means adjustably to secure the socket clamping members together adjacent the ends thereof.

3. A device of the class described comprising a yoke member with parallel extremities, the extremities of which are reduced in width adjacent the ends thereof, a pair of socket clamping members adjustable with respect to each other and each having extremities to engage the edges of the yoke member in the portion of the reduced width thereof, the clamping members being less in width than the length of the reduced portion of the yoke member so that they are adjustable along the yoke member, and means to secure the clamping members together for gripping a socket and to grip the edges of the yoke member whereby they are adjustably positioned with respect thereto.

4. In a fixture device, the combination of a U-shaped yoke member having portions of reduced width adjacent the extremities thereof with a shouldered portion at the end, of socket clamping members adjustable along said portion of reduced width, and a single fastening device at each end to secure the socket clamping members together to grip the socket and to clamp them against the extremities of the U-shaped member in the reduced portion, the shoulder preventing them from becoming disengaged from the yoke member.

5. In an electric fixture, a single rigid member with parallel extremities, a lamp socket, means to give the socket a double vertical adjustment in the extremities, and a shade holding device having a vertically adjustable connection with the extremities of said member.

6. A device of the class described comprising a single rigid yoke-shaped member with parallel extremities, a shade-holding device with corresponding parallel holding extremities, and means to secure the corresponding parallel extremities together at different heights.

7. In a device of the class described, the combination of a rigid U-shaped member, a shade-holding device comprising parallel supporting arms, means to secure the parallel supporting arms to the extremities of the U-shaped member at different heights, and locking means for the said securing means.

8. In a device of the class described, the combination with a U-shaped member having a perforation in each extremity, of a shade-holding device having corresponding supporting arms with threaded perforations therein, fastening screws movable freely

through the perforations in the U-shaped member and engaging in the threaded perforations, and locking means disconnected from and movable over the heads of the 5 screws to prevent their removal.

9. In a device of the class described, the combination with a U-shaped supporting member, of a shade-holding device adjustable with respect thereto, means for securing 10 the device in any adjusted position, adjustable shade grippers in connection with the device, and means for locking the securing means between the U-shaped member and the device and for covering the adjusted 15 shade holder.

10. In a device of the class described, the combination with a single U-shaped supporting member, of a socket clamp adjustable at various heights in the member, and 20 a shade-holder adjustable in height with respect to the member.

11. In a device of the class described, the combination with a U-shaped supporting member, of an adjustable socket clamp comprising 25 a pair of members adjustably secured together and gripping the extremities of the member, an adjustable shade-holder with parallel supporting arms extending between the said securing means and the extremities of the member, and means to secure the said arms adjustably to the extremities of said member.

12. In a device of the class described, the combination of a U-shaped supporting member having a flattened perforated portion intermediate the ends, and a headed nut threaded internally and externally adapted 35 to be inserted through the perforation in the member and having an angular headed portion disposed adjacent the member, the sides of the member being bent over to engage the opposite angular faces of the head of the nut to hold it firmly in position with respect to the member.

45 13. A device of the class described comprising a U-shaped holder with a perforated intermediate portion, a fastening nut secured thereto and extending through the perforation, a shade-holder having upwardly extending arms, and means to secure and vertically adjust the shade holder in the extremities of the U-shaped member.

55 14. A device of the class described comprising a U-shaped holder with a perforated intermediate portion, a fastening nut secured thereto and extending through the perforation, a vertically adjustable shade holder, and a vertically adjustable socket clamp having fastening devices to secure it 60 to the extremities of the U-shaped member.

15. A device of the class described comprising a U-shaped holder with a perforated intermediate portion, a fastening nut secured thereto and extending through the 65 perforation, a shade-holder comprising arms

corresponding to the extremities of the U-shaped member, means adjustably to secure the holder to the said member, a socket clamp comprising a pair of members adjustable lengthwise of the U-shaped member, and fastening devices adjacent the ends thereof to secure the members adjustably together and to clamp the members in any adjusted position against the extremities of the U-shaped member. 70

16. In a device of the class described, the combination with a U-shaped yoke member having a perforated portion intermediate the ends, a headed nut adapted to be inserted through the perforation threaded internally 80 and externally and secured to the yoke member, a lamp socket, insulated conductors leading therefrom and adapted to extend through the nut, a socket clamping device adjustable with respect to the member, 85 means to clamp the socket adjustably in position and in adjusted position with respect to the yoke member, a shade-holding device adjustable with respect to the yoke member, and adjustable shade-holding members in 90 connection with said shade-holding device. 75

17. In a device of the class described, the combination with a U-shaped holder having a perforated intermediate portion, a headed nut adapted to be inserted through the perforation and secured to the member, having external and internal threads, a perforated shade disposed upon the nut, means upon the nut to protect the shade on both sides thereof, and a locking nut movable on the other nut to secure the shade in place 100 against the yoke member. 95

18. In a device of the class described, the combination with a U-shaped yoke member having a perforated intermediate portion, 105 of a headed supporting member adapted to be inserted through and extending beyond the yoke member, a shade-holding device comprising arms corresponding to the extremities of the yoke member, means adjustably to secure the shade-holder to the yoke member, a lamp socket, conductors extending therefrom through the supporting member; a socket clamping device comprising a pair of members, and means to clamp them 110 about the socket against the edges of the extremities of the yoke member, the socket being movable in the socket clamping device and the socket clamping device being separately adjustable with respect to the yoke 120 member, a shade having a perforated portion through which the supporting member is adapted to extend, the shade inclosing the other members and device, washers disposed on both sides of the perforated portion of 125 the shade, and a lock nut movable on the supporting member and adapted to hold the shade in position.

19. In an electric fixture the combination with a yoke member adapted to be centered 130

- and rigidly held, of a variable support for the yoke member comprising a plate having an elongated slot extending from the center toward one side thereof, lateral slots corresponding to the elongated slots, and fastening screws adapted to be inserted through said lateral slot for securing the support rigidly in position. 50
20. In a device of the class described, the combination with a yoke member of an adjusted socket-supporting device, and an adjustable shade-holding device, of a variable support for the yoke member comprising a plate having an elongated slot extending from the center toward one side thereof, lateral slots, and fastening screws adapted to be inserted through said lateral slots for securing the support in position. 55
21. In a device of the class described, the combination with a yoke member having a perforated portion intermediate the ends, a nut adapted to be inserted through the perforation threaded externally and secured to the yoke member through its perforation, a lamp socket, insulated conductors leading therefrom and adapted to extend through the nut, means to clamp the socket and to secure it adjustably in position with respect to the yoke member, a shade supporting device vertically adjustable with respect to the yoke member, and adjustable shade-holding members in connection with said shade supporting device. 60
22. An electric fixture comprising a rigid supporting yoke, a lamp socket clamp adjustable in the yoke, and a shade holder adjustably supported by the yoke. 65
23. An electric fixture comprising a supporting yoke, a lamp socket clamp adjustable in the yoke, and shade holding means also supported by the yoke and adjustable with respect thereto independently of the clamp. 70
24. In an electric fixture, the combination with a supporting yoke having parallel depending arms, a socket clamp adjustable in the arms and securable thereto in gripping a socket, and shade holding means attachable also to the arms and depending below the extremities thereof and adjustable relatively to the clamp and the yoke. 75
25. In an electric fixture, a supporting yoke, shade holding means adjustable in the yoke, a socket clamp adjustable in the yoke, a lamp socket slidable in the clamp for adjustment and held in adjusted position when the clamp is secured to the yoke. 80
26. In an electric fixture, a supporting yoke with depending arms, a socket clamp engaging the arms and adjustable therein, a socket engaged by the clamp and slidable in the clamp for adjustment, and a vertically adjustable focusing shade holder also supported by the yoke arms and independently adjustable with respect to the socket. 85
27. In an electric fixture, a supporting yoke with parallel arms, a lamp socket, and a socket clamp having portions to engage the socket and other portions to engage the arms and fastening means by which the socket and arms are simultaneously gripped. 90
28. In an electric fixture, the combination with a fixed support, of a shade holder supported thereby, and a vertically adjustable lamp socket clamp comprising a pair of members adapted to grip both the support and a lamp socket to focus a lamp with respect to the shade by the movement of the socket in the clamp and by the movement of the clamp. 95
29. In an electric fixture, the combination with a yoke having parallel arms, of a lamp socket, and a vertically adjustable socket clamp comprising a pair of members adapted to grip both the arms and the socket to vary the position of a lamp with respect to the yoke by the movement of the socket in the clamp and by the movement of the clamp in the arms. 80
